UNITED STATES PATENT OFFICE

HERMAN L. KUTTER, OF HAMILTON, OHIO, ASSIGNEE TO BELLOIT IRON WORKS, OF
BELLOIT, WISCONSIN, A CORPORATION OF WISCONSIN

FOURDRINIER PAPER MACHINE

Application filed February 23, 1928. Serial No. 256,068.

This invention relates to a paper machine and more particularly to the construction of the Fourdrinier section of a paper machine.

Heretofore, it has been general practice to construct the Fourdrinier section or web forming part, as a single unit capable of being elevated at the breast roll end, or more recently, at the couch roll end, to vary the pitch of the wire. Owing to the great length of modern Fourdriniers, this practice of elevating the Fourdrinier section from one end makes it necessary to use heavy side beams, usually I beams or deep channel beams, in the construction of the supporting frame.

The present invention has for its object to provide a lighter supporting structure formed of tubular beams and further to provide a supporting frame formed in hinged sections and adapted to be elevated at its intermediate hinged points, thus avoiding the necessity of using heavier structural material.

Other and further important objects of this invention will be apparent from the disclosures in the specification and the accompanying drawings.

This invention (in a preferred form) is illustrated in the drawings and hereinafter more fully described.

On the drawings:

Figure 1 is a front side diagrammatical elevational view of a Fourdrinier structure embodying the principles of this invention;

Figure 2 is an enlarged broken sectional view taken on line II—II of Figure 1 with parts in elevation;

Figure 3 is a sectional view taken on line III—III of Figure 2 with parts dotted to show the operation;

Figure 4 is an enlarged fragmentary front elevational view; and

Figure 5 is a sectional view taken on line V—V of Figure 4.

The reference numeral 1 indicates as a whole a Fourdrinier structure embodying the principles of my invention and comprising a sectional tubular frame pivotally supported at the breast roll end, as at 2, and at the couch roll end, as at 3. Said frame is formed in two sections, a table roll section A having

tubular side beams 4 adapted to support the usual table rolls 5 and a suction box section B having tubular side beams 6 for supporting the usual suction boxes 7. Said sections A and B are hingedly connected, as at 8, 55 by means of pivot pins 9 extending through abutting flattened forked ends 10 and 11 formed upon the tubular side beams 4 and 6, respectively, (Figure 2). Said pivot pins 9 are supported by jack screws 12 and 13, 60 which are provided with flattened heads 14 and 15 respectively, for receiving the forked ends 11.

Said jack screws 12 and 13 are mounted in front pedestal 16 and a rear sleeve casting 17, respectively, the front pedestal 16 being provided with a forwardly and rearwardly extending hollow base portion 18 in which are mounted toothed wheels 19 for engagement with grooved tracks 20. One of said toothed wheels 19 is adapted to be driven through a gear 22 from a sprocket gear 23 mounted on a power driven shaft 24. Both the front pedestal 16 and the rear sleeve casting 17 are provided with rollers 25 adapted 70 to rest upon and roll over elevated tracks 26. A stationary rear support 27 is provided with lower spaced rollers 28 upon which said tracks 26 are adapted to rest and upper rollers 29 adapted to bear against the upper 80 flanges of said tracks 26. The forward ends of said tracks 26 are adapted, in normal position, to rest in grooves 30 (Figure 3) formed in a stationary front pedestal 31. Said pedestal 31 is cut away as at 32 to permit the extended base portion 18 to pass inside of the pedestal 31. A rearwardly spaced support 32 having rollers 33 mounted thereon is adapted to support the tracks 26 in rearwardly extended position. 85

The breast roll end of the frame section A is pivoted as at 2 upon pedestals 34 adapted to roll frontwise of the machine, as more clearly disclosed in my copending application, Serial No. 126,544, which was filed August 2nd, 1926 now Patent No. 1,729,350, granted Sept. 24, 1929. 95

In a similar manner, a pair of pedestals 35 supports the couch roll end of the frame section B for pivotal movement about the 100

point 3, said pedestals 35 also being provided with rollers for lateral removal frontwise of the machine. The shaft 24 extends between said pedestals 34 and 35 to operate the various rollers in the respective pedestals 34, 16 and 35.

The method of removing the Fourdrinier structure 1 in order to change the wire, indicated by the reference numeral 36, is apparent and needs no detailed explanation.

Briefly, the old wire is removed and the breast roll 37 and couch roll 38 moved relatively toward each other in any of the well-known ways to provide for the stringing of a new wire. The Fourdrinier structure 1 is then moved out as a unit, the pedestals 34, 16 and 35 bearing the greater part of the weight and the rear side of the Fourdrinier structure 4 rolling out over the tracks 26 and

similar tracks (not shown) associated with the pedestals 34 and 35 respectively. Said tracks are then withdrawn rearwardly to rest upon the rollers 33 of the pedestal 32 and similar rollers (not shown) for the tracks 39 and 40.

Abutments 41 are formed on the pedestals 16, 34 and 35 to support the rear side of the Fourdrinier structure 1 in laterally removed position when the tracks are in their rearward position. The new wire is then strung in place, the tracks moved into place and the Fourdrinier structure rolled back into its normal position again.

The mechanism for adjusting the height of the jack screws 12 and 13 to vary the pitch of the wire includes gears 42 and 43, respectively, adapted to engage with worms 40 formed on a transverse bar 44. Said bar 44 may be manually rotated by the application of a crank (not shown) to its forwardly extended end 39. By raising the jack screws 12 and 13, the frame sections A and B are elevated at their pivotally connected ends as shown in dotted lines in Figure 3. Since the pivot point 2 near the breast roll end of the Fourdrinier is fixed, the amount of variation in pitch of the wire and table roll section A is regulated solely by operation of said jack screws 12 and 13. The pitch of the wire as it passes over the suction boxes 7 is not so important, since the web of paper on the wire has already been practically formed before reaching the suction boxes. The pitch of the wire over the table rolls 5, however, is extremely important in the obtaining of a well formed sheet and it should be noted that the pitch can be more easily adjusted and a greater variation in pitch obtained by adjustment of the jack screws 12 and 13 than if the Fourdrinier structure were elevated at one of its extreme ends.

In addition to this advantage of easy adjustment of the pitch, the above construction also has a further advantage of being relatively lighter than usual structures owing to

the fact that tubular beams and tie rods are used in place of the customary I-beams or channel beams.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

1. In a removable type Fourdrinier paper machine, a frame formed in two hinged sections for supporting table rolls and suction devices respectively, means for adjusting the height of said frame at its hinged points and means for laterally removing said frame as a unit.

2. In a removable type fourdrinier, a sectional supporting frame carrying the table rolls and suction boxes, the respective sections being pivotally connected to each other, means pivotally supporting the extremities of said frame, means for laterally removing said supporting frame as a unit and vertically adjustable screws supporting the pivotal connections between said sections.

3. In a Fourdrinier paper machine, a supporting structure including end and intermediate pedestals, aligned side beams pivotally mounted at their outer ends to said pedestals and provided with inner abutting ends, elevating means associated with said intermediate pedestals and common means pivotally connecting said inner abutting ends to said elevating means.

In testimony whereof I have hereunto subscribed my name.

HERMAN L. KUTTER.
